UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR CUP-FEED MACHINES.

1,246,302.

Specification of Letters Patent. Patented Nov. 13, 1917.

Application filed September 24, 1914. Serial No. 863,830.

To all whom it may concern:

Be it known that I, JAMES R. MOFFATT, a citizen of the United States, residing at Chicago, in the county of Cook, State of Illinois, have invented certain new and useful Improvements in Feeding Mechanism for Cup-Feed Machines, of which the following is a description, reference being had to the accompanying drawings and to the figures of reference marked thereon.

The invention relates to new and useful improvements in cup feed machines and more particularly to the feeding mechanism therefor.

An object of the invention is to provide means for positively driving the outer feed cup from the mechanism which operates the inner feed cup, which driving mechanism is so constructed as to permit the outer feed cup to be freely moved toward and from the inner feed cup for the insertion and withdrawal of the material.

A further object of the invention is to provide a driving mechanism of the above character which includes a flexible shaft for connecting the feed cups, which flexible shaft is located so as not to interfere with the free travel of the fabric between the feed cups, and which also permits the feed cups to be moved relative to each other.

A further object of the invention is to provide a feeding mechanism of the above character with an inclosed flexible casing for the flexible shaft.

These and other objects will in part be obvious and will in part be hereinafter more fully disclosed.

In the drawings:

Figure 1 is a view in side elevation with certain parts broken away of a machine having my improvements applied thereto.

Fig. 2 is a plan view of the forward portion of the same.

Fig. 3 is a front view of the upper portion of the machine.

Fig. 4 is a sectional view through the supporting bracket for the outer feed cup showing the driving connection between the flexible shaft and the feed cup.

Fig. 5 is a perspective view of the supporting bracket also showing the intermediate gears.

Fig. 6 is a detail in side elevation showing

a slightly modified form of the supporting bracket for the outer feed cup. 55

Fig. 7 is a view partly in plan and partly in section showing a different arrangement of the flexible shaft from that shown in Figs. 1 to 5, inclusive.

Fig. 8 is a detail in vertical section 60 through the outer feed cup and the supporting bracket therefor, as shown in Figs. 6 and 7.

The invention consists generally in providing feed wheels which have serrated co-operating surfaces for clamping and feeding a fabric. Means is provided for intermittently rotating one of the feed wheels and a flexible shaft is provided for connecting said rotating feed wheel to the co-operating feed wheel, so that both feed wheels will be rotated in unison. This flexible shaft is so arranged relative to the supporting brackets for the feed wheels that the feed wheels may be moved toward and from each other to a certain extent to permit the insertion and withdrawal of the fabric being stitched. 65 70 75

Referring more in detail to the drawings, Fig. 1 shows a machine of the cup feed type 80 embodying the invention. The machine consists of a main casing 1 in which is mounted a main driving shaft 2. The machine is provided with an inner feed cup or wheel 3 and an outer feed cup or wheel 4. Reciprocating directly above the feed cups is a needle 5 which is moved back and forth across the meeting edges of the feed cup by suitable mechanism operated from the main shaft 2. Co-operating with the needle 5 is 85 a thread carrying looper 6. This thread carrying looper is of the usual type in a feed cup machine and has a movement into the needle loop, then upward and over the edge of the fabric and then downwardly to a position where the needle enters the looper thread loop. The loop is also given its movements from the main shaft 2. The looper thread is led through a suitable tension 7 while the needle thread is led through a tension 8. The needle tension may be released by a slide rod 9 which carries a plate 10 adapted to separate the tension disk. The rod 9 is mounted in suitable brackets and is moved endwise for releasing the tension by a lever 11 which is pivoted to the 90 95 100 105

frame of the machine. The above features form no part of the present invention.

The feed cup or wheel 3 is mounted on the upper end of a shaft 12, as shown in dotted lines in Fig. 1, and this shaft is journaled in a bracket 13 which is secured to the main casing 1. At the lower end of the shaft 12 there is a flange disk 14 with which cooperates an intermittently gripping arm which 10 in turn is oscillated by a link 15 connected to a rock shaft 16 which rock shaft is oscillated by a link 17 cooperating with an eccentric on the main shaft 2. A suitable gripping arm is also provided for preventing 15 retrograde movement of the feed cup. These parts are also of the usual construction in this type of machine.

The outer feed cup 4 is journaled in a support 18. This support is provided with 20 an inwardly projecting arm 19 which is clamped to a pivot shaft 19^a which is journaled in a bracket 20 adjustably attached to the main casing 1 by screws 22. These screws 22 pass through slots 23 in the 25 bracket and when the screws are loosened the bracket may be shifted so as to vary the position of the support for the outer cup. The main casing 1 is provided with a recess 24 which receives the bracket. This 30 recess permits the bracket 20 to be adjusted as above noted but holds the same from up and down movement on its supporting screw. The pivot shaft of the support 18 extends beyond the bracket 20 and an arm 35 25 is fixed thereto. This arm is adapted to be connected to a suitable treadle or knee shift. A flat spring 26 engages the under face of the arm 25. This spring is fulcrumed on an adjustable screw 27 and extends 40 underneath a projecting lug 28 carried by the main casing 1. The spring 26 throws the arm 25 upwardly and this swings the support 18 about its pivot so as to bring the feed cups 4 and 5 into contact, or to 45 grip a fabric to be stitched therebetween. A stop 29 carried by the arm 25 engages the under face of the bracket 20 and limits the movement of the feed cup 4 toward the feed cup 3. A stop 30 also carried by the 50 arm 25 engages the upper face of the bracket 20 and limits the outward movement of the feed cup 4 away from the feed cup 3.

Mounted in the support 18 is a shaft 31. This shaft 31 is connected to a gear wheel 55 32 at its lower end. The support 18 is cut away to form a recess for the gear 32, see Fig. 5. This gear 32 meshes with a gear wheel 33 which is journaled on the support and the gear wheel 33 in turn meshes with a gear 60 34. The gear wheel 34 is provided with a hub 35 which extends through the support, and a screw 36 holds the gear wheel in place. The feed cup or wheel 4 is clamped to the upper face of 65 the gear wheel 34 by screws 37, see Fig. 4.

At the upper end of the shaft 31 there is a sleeve coupling 38 which is clamped to the shaft by a set screw 39. A flexible shaft 40 extends into this coupling and is clamped thereto by a set screw 41. The other end of the flexible shaft 40 is secured to a sleeve coupling 42 in a similar manner, and this sleeve coupling is attached to the upper end of a shaft 43 which is mounted in a suitable bearing in the main casing. The shaft 40 is bowed in substantially U shape and lies in a vertical plane, and by this bowing of the shaft I am able to transmit the motion between the vertical shaft carrying the inner feed cup and the vertical shaft carrying the outer feed cup. The shaft 43 carries a gear wheel 44 which meshes with a gear wheel 45 journaled in the main casing, and the gear wheel 45 in turn meshes with a gear wheel 46 on the shaft 12 which carries the feed cup 5. As the feed cup 5 is intermittently rotated the gears 45 and 44 will rotate the shaft 43, which in turn will rotate the flexible shaft 40 and this will impart a similar intermittent rotation to the shaft 31, which through the gears 32 and 33 will rotate the outer feed cup. It will thus be apparent that the outer feed cup is rotated in unison with the inner feed cup.

The flexible shaft 40, as herein shown, is located above the support for the outer feed cup and the bracket which carries the same. Therefore, this flexible shaft will not interfere in any way with the free passage of the material or fabric between the feed cups. Inasmuch as this shaft is flexible the support 18 may be readily swung about its pivot on the bracket 20 so as to separate the feed cups or so as to permit the feed cups to clamp the fabric which is to be stitched. The flexible shaft, therefore, not only provides means for rotating the outer feed cup in unison with the inner feed cup, but this means is so constructed as to permit the free movement of the outer feed cup toward and from the inner feed cup. A flexible brass casing 47 surrounds the flexible shaft 40. This casing freely rests at its ends on the couplings 38 and 42. A bracket arm 49 is secured to the support for the tensions and this bracket arm extends upwardly and is formed with a hook 50 which engages about the casing.

A suitable guide 48 incloses the gear on the shaft supporting the inner feed cup. The gears for the outer feed cup are housed in the supporting bracket therefor.

As clearly shown in Figs. 2 and 3 of the drawings, the support 18 is so constructed that the vertical portion thereof carrying the shaft 31 is at one side of the stitching point as viewed by the operator when in front of the machine. In other words, the operator sits directly in front of the machine, that is, in front of the outer feed cup,

and in order that there may be no obstruction to the ready view by the operator of the stitching elements, this support for the outer feed cup is set at one side of a vertical plane containing the path of the needle. 5 The intermediate gear wheel 33 permits this offsetting of the support for the outer feed cup.

In Figs. 6 to 8 of the drawings, I have 10 shown a slightly modified form of the invention. In these views the outer feed cup is shown as connected directly to the vertical shaft which drives the same and as a consequence the support for the vertical shaft is 15 directly in front of the stitching point or in a vertical plane containing the path of the needle. The arm 19 carrying the support 18 is deflected laterally, so that the axis of the vertical shaft 31 lies in a vertical plane containing the path of the needle, and the feed cup 4 is clamped at the lower end of this 20 vertical shaft 31. In Fig. 8 of the drawings I have shown the shaft 31 as extending below the support 18, and the feed cup 4 is 25 clamped thereto by a screw 51.

The pivot shaft 19^a between the arm 19 and the supporting bracket 20 lies in a vertical line $x-x$, which is slightly forward of the meeting edges of the feed cups 3 and 4, 30 and also lies below a line connecting the lower ends of the flexible shaft. This positioning of the pivot shaft 19^a causes the outer feed cup when moved away from the inner feed cup to move downwardly and outwardly 35 in approximately a straight line, and prevents the bending or breaking of the needle, and the flexible shaft aids in separating the feed cups.

It will be noted that the couplings 38 and 40 42 are in substantially the same horizontal plane, and this permits the flexible shaft to be bowed in a true arc, so that said shaft will ride free at all points within the casing therefor.

45 It is obvious that minor changes in the details of construction may be made, without departing from the spirit of the invention as set forth in the appended claims.

Having thus described my invention, what 50 I claim as new and desire to secure by Letters Patent is:

1. A sewing machine including feed wheels between which a fabric is clamped and fed to a stitching mechanism, a shaft of flexible 55 material connecting said feed wheels, means for rotating the feed wheels, and means whereby the feed wheels may be moved relative to each other to permit the insertion and withdrawal of the fabric between the feed 60 wheels.

2. A sewing machine including feed wheels between which a fabric is clamped and fed to a stitching mechanism, a shaft of flexible material connecting said feed wheels, means 65 whereby the feed wheels may be moved relative to each other to permit the insertion and withdrawal of the fabric between the feed wheels.

the feed wheels may be moved relative to each other to permit the insertion and withdrawal of the fabric between the feed wheels, and a flexible casing for inclosing said flexible shaft.

70

3. A sewing machine including in combination, a casing, an inner feed cup supported thereby, an outer feed cup coöperating with said inner feed cup, a support for said outer feed cup, means for moving the support to 75 separate the feed cups, a single shaft of flexible material for connecting the feed cups, and means for rotating the feed cups.

4. A sewing machine including in combination, a casing, an inner feed cup supported thereby, an outer feed cup coöperating with said inner feed cup, a support for said outer feed cup, means for moving the support to 80 separate the feed cups, a single shaft of flexible material for connecting the feed cups, 85 means for rotating the feed cups, and a flexible casing for inclosing said shaft of flexible material.

5. A sewing machine including in combination a supporting casing, an inner feed 90 cup mounted to rotate about a vertical axis, means for intermittently rotating the same, an outer feed cup coöperating with said inner feed cup, a support for said outer feed cup, a bracket connected to said casing and 95 extending over said inner feed cup, an arm projecting from said support and pivotally connected to said bracket, means for swinging said arm so as to move the outer feed cup relative to the inner feed cup toward 100 and away from the same, and a flexible shaft for connecting said inner feed cup to said outer feed cup, said flexible shaft being located above the feed cup.

6. A sewing machine including in combination a supporting casing, an inner feed cup mounted on said supporting casing, means for intermittently rotating said inner feed cup, an outer feed cup coöperating with said inner feed cup, a needle reciprocating 105 back and forth above said feed cups, a support for said outer feed cup, a vertical shaft mounted in said support, said vertical shaft being located at one side of a vertical plane containing the path of the needle, gears for 110 connecting said vertical shaft to said outer feed cup, and a flexible shaft for driving said vertical shaft from the means for operating the inner feed cup.

7. A sewing machine including in combination a supporting casing, an inner feed cup, a vertical shaft for supporting said inner feed cup, means for intermittently rotating said vertical shaft, a second vertical shaft mounted in said supporting casing, 115 gears for connecting said second vertical shaft to said first vertical shaft, an outer feed cup coöperating with said inner feed cup, means for supporting said outer feed cup whereby it may be moved toward and 120

125

from said inner feed cup, a vertical shaft connected to the outer feed cup, and a single U-shaped flexible shaft for connecting the vertical shaft for the outer feed cup to said second vertical shaft mounted in said supporting casing.

8. A sewing machine including in combination a supporting casing, an inner feed cup, a vertical shaft for supporting said inner feed cup, means for intermittently rotating said vertical shaft, a second vertical shaft mounted in said supporting casing, gears for connecting said second vertical shaft to said first vertical shaft, an outer

10 inner feed cup coöperating with said inner feed cup, means for supporting said outer feed cup whereby it may be moved toward and from said inner feed cup, a vertical shaft connected to the outer feed cup, a flexible 15 shaft for connecting the vertical shaft for the outer feed cup to said second vertical shaft mounted in said supporting casing, said flexible shaft being disposed above the feed cups, a casing surrounding said flexible

20 shaft, and means for steadyng said casing.

9. A sewing machine including in combination a supporting casing, an inner feed cup, an outer feed cup, a support for said outer feed cup located above said feed cup,

30 means for pivotally supporting the support for the outer feed cup, the pivotal point thereof being located outside of a vertical plane tangential to the feed cup at the stitching point.

35 10. A sewing machine including in combination a main supporting casing, an inner feed cup mounted to rotate about a vertical axis, means for supporting said inner feed cup, an outer feed cup coöperating with

40 said inner feed cup, a support for said outer feed cup located above said feed cup, a bracket attached to said casing, means for pivotally connecting the support for the outer feed cup to said bracket, said pivotal

45 connection being disposed in front of a vertical plane tangential to the feed cups at the stitching point, and means for moving said support about its pivotal point, said means including a spring for normally 50 pressing the outer feed cup toward the inner feed cup.

11. A sewing machine including in combination a supporting casing, an inner feed cup mounted to rotate about a vertical axis,

55 means for rotating the same, an outer feed cup coöperating with said inner feed cup, a support for said outer feed cup arranged above said cups, and a driving connection between said cups and arranged above said

60 support.

12. A sewing machine including in combination a supporting casing, an inner feed cup mounted to rotate about a vertical axis,

65 means for rotating the same, an outer feed cup coöperating with said inner feed cup,

and driving connections between said cups, said connections including a flexible shaft and separate sets of gearing connecting the ends of the shaft with the respective cups.

13. A sewing machine including in combination a supporting casing, an inner feed cup mounted to rotate about a vertical axis, means for rotating the same, an outer feed cup coöperating with said inner feed cup, a support for said outer feed cup and a 70 flexible shaft for imparting the movements of the inner cup to the outer cup, said flexible shaft being bowed upwardly from the cups and arranged in a vertical plane.

14. A sewing machine, including in combination a supporting casing, an inner feed cup mounted to rotate about a vertical axis, an outer feed cup coöperating with said inner feed cup, and driving connections between said cups including two vertical 80 shafts operatively connected to the respective cups, and a driving connection of flexible material between said vertical shafts.

15. A sewing machine including in combination a supporting casing, an inner feed 90 cup mounted to rotate about a vertical axis, an outer feed cup coöperating with said inner feed cup, a support for the outer cup offset from a center line through the casing, and means for imparting the rotary 95 movements of the inner cup to said outer cup.

16. A sewing machine including in combination a supporting casing, an inner feed cup mounted to rotate about a vertical axis, 100 means for rotating the same, an outer feed cup coöperating with said inner feed cup, a driving connection between said feed cup including a flexible shaft, a casing for said shaft, the ends of said shaft being in substantially the same horizontal plane.

17. A sewing machine including in combination, a supporting casing, an inner feed cup, an outer feed cup, a support for said outer feed cup, means for pivotally supporting the support for the outer feed cup at a point above the cups, the pivotal point thereof being located outside of a vertical plane tangential to the feed cup at the stitching point, and driving connections between the 115 inner feed cup and the outer feed cup.

18. A sewing machine including in combination, a main supporting casing, an inner feed cup mounted to rotate about a vertical axis, means for supporting said inner feed 120 cup, an outer feed cup coöperating with said inner feed cup, a support for said outer feed cup located above said feed cups, a bracket attached to said casing, means for pivotally connecting the support for the outer feed

125 cup to said bracket, said pivotal connection being disposed in front of a vertical plane tangential to the feed cups at the stitching point, means for moving said support about its pivotal point, said means including a 130

spring for normally pressing the outer feed cup toward the inner feed cup, and driving connections between the inner feed cup and the outer feed cup.

19. A sewing machine including in combination, a supporting casing, an inner feed cup mounted to rotate about a vertical axis, an outer feed cup coöperating with said inner feed cup, a support for said outer cup 10 pivotally supported on said casing, and driving connections between said cups including front and rear solid shafts, and a flexible connection between said solid shafts, the point of connection between the flexible connection and the front shaft being disposed above the pivot of the outer cup.

20. A sewing machine including in combination, a supporting casing, an inner feed cup mounted to rotate about a vertical axis, an outer feed cup coöperating with said 20 inner feed cup, a support for said outer cup pivotally supported on said casing, driving connections between said cups including front and rear solid shafts, and a flexible

connection between said solid shafts, the 25 pivot of the outer cup being disposed between the ends of said flexible connection and below the point of connection between the flexible connection and the front shaft.

21. A sewing machine including in combination, a supporting casing, an inner feed cup mounted to rotate about a vertical axis, an outer feed cup coöperating with said 30 inner feed cup, a support for said outer cup pivotally supported on said casing, driving 35 connections between said cups including front and rear solid shafts, and a flexible shaft connection between said vertical shafts, said flexible shaft being bowed upwardly and having its point of connection 40 with said vertical shafts disposed in a horizontal plane above the pivot of the outer cup.

In testimony whereof, I affix my signature in the presence of two witnesses.

JAMES R. MOFFATT.
